3 SHEETS—SHEET 3.

UNITED STATES PATENT OFFICE.

OTTO EICK, OF BALTIMORE, MARYLAND.

BOTTLE-CLEANING MACHINE.

No. 927,646.

Specification of Letters Patent.

Patented July 13, 1909.

Application filed March 20, 1908. Serial No. 422,323.

To all whom it may concern:

Be it known that I, OTTO EICK, citizen of the United States, residing at Baltimore, in the State of Maryland, have invented certain new and useful Improvements in Bottle-Cleaning Machines, of which the following is a specification.

My present invention pertains to an improved bottle-cleaning machine, the construction and advantages of which will be hereinafter set forth, reference being had to the annexed drawings, wherein:

Figure 1 is a side elevation of the machine, parts being broken away and shown in section; Fig. 2 a transverse vertical sectional view, taken on the line *a—a* of Fig. 1; Fig. 3 a similar view, taken on the line *b—b* of Fig. 1; Fig. 4 a horizontal sectional view, taken on the line *c—c* of Fig. 1; Fig. 5 a vertical sectional view of the main valve, taken on the line *d—d* of Fig. 6; Fig. 6 a similar view, taken on the line *e—e* of Fig. 5; Fig. 7 a sectional elevation, showing a modified arrangement of the spindle-driving mechanism; Fig. 8 a detail vertical sectional view of one of the mouth-pieces; and Fig. 9 a similar view, showing a modified form of mouth-piece.

The main object of the present invention is to provide an apparatus wherein the bottles, sustained in crates, may be introduced into the machine in an inverted position and therein subjected to a spray of water or the like, and to the action of a series of spindle-brushes which are passed into the bottles.

A further object of the invention is to provide means for automatically raising and lowering the crate-sustaining means, whereby the bottles will be first brought into contact with the mouth-piece plate and then carried downward over the spindle-brushes, the brushes remaining fixed except for a rotary motion.

Another object of the invention is to provide means whereby the bottles which are located over the spindle-brushes may be moved downward independently of the other bottles through the major portion of their movement, and as such bottles approach the limit of their movement the other bottles, which are positioned over the spraying nozzles, are drawn down into working relation with said spraying nozzles.

A still further object of the invention is to provide means whereby the bottles which are acted upon by the spindles will be first moved into operative relation with the mouth-pieces

carried by the mouth-piece plate, and the bottles and mouth-piece plate thereafter moved downward so as to cause the spindles to enter the bottles, the bottles being held closely against the mouth-pieces while the spindle-brushes are within the same.

Another object of the invention is to provide hydraulic means for effecting the operations just set forth, said means being under the control of the operator standing at one side of the machine.

In the drawings, 1 designates the base of the machine, and 2, 3 arms or brackets secured to the sides of the base and extending outwardly therefrom, as best shown in Fig. 1. Projecting upwardly from the base are two posts or columns 4 and 5, said posts being surmounted by a top-plate or platform 6, the platform carrying an electric or other motor 7 and having secured to its ends and extending outwardly therefrom arms or brackets 8 and 9.

Secured to the bracket 3 is an arm or plate 10 which extends outward therefrom and forms the support for a pedestal 11, said pedestal having four L-shaped arms 12, Figs. 1 and 3. Ways or guides 13 and 14, Fig. 3, are secured to the upper ends of the oppositely-disposed arms 12 and form a support for a reciprocating plate 15. Said plate is provided on its under face with lugs 16, to which are pivoted L-shaped fingers 17, the long end of said fingers extending downwardly and being beveled, as clearly shown in Fig. 1, in order that as the plate is moved to the right in said figure the finger may swing and ride over the crate, designated by 18, which is then standing below the plate. A strap 19 is secured to the opposite ends of the plate, or to lugs 16, extending upwardly therefrom, said strap passing about a pulley or band-wheel 20, mounted upon a shaft 21, which finds its bearings in arms 22 extending upwardly from the guides or ways 13, 14. A pinion 23 is mounted upon one end of the shaft and a sector-gear or rack 24 meshes therewith, said rack being fulcrumed upon a stub-axle 25, extending outwardly from the member 14. A handle or lever 26 projects from the sector-gear within easy reach of the operator, so that the parts may be actuated to reciprocate the plate and as a consequence move the crates into and through the machine.

A pair of fixed tracks 27 is carried by the arms 12, and standing in line with said

tracks is a second pair of tracks 28, formed of angle-bars, as shown in Fig. 3. A third pair of tracks 31, Fig. 2, is supported in line with the tracks 28 by rods 32, said rods at 5 their lower ends passing through the inwardly-projecting flanges or arms of a sliding frame 33, which latter is mounted and slideable upon the posts or columns 4 and 5. The tracks 31 are normally held in an elevated 10 position, in alignment with the tracks 28, by springs 34 which encircle the rods 32 and bear against the under face of the tracks and upon the upper face of the sliding frame 33. A fourth pair of tracks, 35, formed of angle- 15 bars, similar to the angle-bars shown in Fig. 3, is located to one side of and in alignment with the tracks 31.

When the various tracks are in the positions shown in Fig. 1, the crates may be advanced into and through the machine, and 20 will come to rest in the positions shown in said figure, wherein the bottles of the first crate will be over the nozzles of the first spraying device, the bottles in the second 25 crate standing in alignment with the mouth-pieces and the spindle-brushes, and the bottles in the third crate in alignment with the nozzles of the final spraying device.

The tracks 28 are each provided with a pair 30 of upwardly-extending links 36 which, where they come together at their upper ends, have attached to them a spring 37, the springs in turn being suspended from the outwardly-projecting ends of the brackets 9, see Figs. 1 35 and 3. Each of said tracks 28 is provided with an outwardly-extending lug 38, and a rod 39 passes through each of said lugs, the lower end of each rod being threaded into that arm of the frame 33 which stands below 40 the rod. Each rod is provided with adjustable collars 40 and 41, the latter being below the lug 38 and the other located adjacent to the upper end of the rod. A like arrangement of parts is employed in conjunction 45 with the tracks 35 at the opposite end of the machine, the springs which serve to hold said tracks, or the frame which they form, in a raised position being secured to the outer ends of the brackets 8.

50 When the frame 33 is in its elevated position, or that shown in Fig. 1, the collars 41 contact with the lugs 38 and thus hold the various tracks in alignment, so that the crates may be readily passed from one track 55 to another when the sector-gear and its co-acting parts are operated. The collars 40 are so positioned that the frames which carry the first and last crates remain elevated until the frame 33 is moved downward to nearly 60 its full extent, when said collars come into contact with the lugs 38 and draw the frames downwardly against the action of the sustaining springs.

A frame 44 is slidably mounted upon the 65 posts or columns 4 and 5, and a presser-plate

45 is likewise mounted upon said posts or columns immediately below the frame 44. The frame and the plate are connected to each other by coiled springs 46, which springs serve normally to hold the parts in the positions shown in Fig. 2, with the plate out of contact with the bottles, which are in an inverted position below the plate. The frame 44 carries a cylinder 47, in which is mounted a piston 48, its rod 49 being connected to 70 the presser-plate. A pipe 50 opens into the upper end of the cylinder, said pipe being connected to a pipe 51 by a hose or other flexible connection 52, pipe 51 leading to a valve 53, hereinafter referred to in detail. 75 Frame 44 is adjustably secured to the upper ends of a pair of rods 54, said rods passing through lugs formed upon the sides of the frame 33 and being secured thereto by bolts or adjusting screws, as shown in Figs. 1 and 2. It will thus be seen that the frames 33 and 44 are held a definite distance apart, but that the plate 45 may be moved downward independently of the frames; and thus clamp the bottles in the crates, preparatory to their 80 being moved downwardly into contact with the mouth-pieces 55, which are normally held in an elevated position above the bottom of the frame 33 by springs 56. The downward movement of the presser-plate 45, 85 therefore, first clamps the bottles in the crates and upon a further downward movement forces the crates and the tracks 31 downwardly so that the mouths of the bottles enter the mouth-pieces, ready to receive 90 the spindle-brushes.

To the lower end of each of the rods 54 is pivotally connected a link 57, each link in turn being pivotally connected to one end of an arm or lever 58, said lever being fulcrumed upon shafts mounted in brackets 59, secured to a fixed portion of the machine, as seen in Fig. 4. A counter-weight 60 is mounted upon the opposite end of each of the levers, the weights being so adjusted as to normally 105 elevate the frames with the crate and bottles therein.

A cylinder 61 is mounted upon the arm or plate 10, and the piston-rod 62, connected to the piston 63 mounted in the cylinder, is pivotally connected to a link 64, said link in turn being pivotally connected to a cross-bar 64^a secured to the levers 58, see Fig. 4. A pipe 65 opens into the lower portion of the cylinder 61 and, as shown in Fig. 1, leads to 110 the valve 53. Said valve, which is shown in detail in Figs. 5 and 6, serves first to admit water or other fluid under pressure to the upper cylinder 47 to force the presser-plate 45 downwardly, and bring the bottles into contact with the mouth-pieces, as above set forth. This position is shown in dotted lines 115 in Fig. 5. A further movement of the valve in the direction of the arrow Fig. 5, will throw the pipe 65 into communication with 120

125 130

an inlet pipe 66, the exhaust pipe 67 at such time being cut off from communication with the inlet pipe and the pipes 51 and 65.

The valve being moved to its full extent, 5 fluid under pressure will be admitted to the lower portion of the cylinder 61, and as a consequence the piston 63 therein will be raised, and through its movement the frames 33 and 44 will be drawn downwardly, causing 10 the spindles 68 to pass into the bottles. A reverse movement of the operating handle of the valve 53 will cause the pipe 65 to be brought into communication with the discharge pipe 67, and the frames 33 and 44 will 15 move in the opposite direction. The pressure in the cylinder 47 will, however, be retained and the valve will be held in such position until the spindles and spindle-brushes have been withdrawn from the bottles; or, 20 in other words, until the bottles have been withdrawn from over the spindles, the spindles and spindle-brushes having no vertical or endwise movement. When the parts occupy this position, the valve is moved to the 25 position shown in full lines in Fig. 5 and the pipe 51 may then exhaust.

The spindles 68 are hollow and provided with openings or perforations at their upper ends and along the upper portions thereof, 30 so that the water entering the box or chamber 69 through pipe 70 and valve 71 may pass out of the spindles and into the bottles.

Each spindle is provided at its lower end with a gear 72 (see Figs. 2 and 4), the four 35 spindles which are nearest the center of the box having their gears in mesh with a centrally-disposed gear 73 mounted upon the upper end of a shaft 74, which latter is driven through bevel-gears 75 and 76, motion being 40 imparted to the gear 76 through a driving shaft 77. The lower ends of the spindles 68 are seated in bushings 68^a which are secured in the upper face of the box or chamber 69. Shaft 77 is provided with the usual fixed and 45 loose pulleys, and is driven from a belt extending from a pulley mounted upon the shaft of the motor 7. The gears 72 of the outermost spindles are driven from the corresponding gears of the innermost spindles by 50 intermediates or idlers 78.

As will be noted, the lower ends of the spindles open into the box 69, so that water may be forced upwardly through said spindles. It is desirable, of course, that the water 55 be not turned into the spindles until the bottles have moved downwardly over the spindles to a greater or less extent, and to effect the automatic turning on and off of the water which passes into the box or chamber 60 through the pipe 70 I secure to the stem of the valve 71 a lever 79, one end of which is in turn connected to one of the levers 58 through a rod 80 that passes loosely through an eye 81 secured upon said lever. Collars 65 82 and 83, secured upon the rod 80 at oppo-

site sides of the eye, serve to actuate the rod in one or the other direction and thereby to open or close the valve 71 at the proper time. Collars 82 and 83 are spaced apart so as to allow for slight movement of the lever 70 independently of the rod and valve.

An overflow pipe 84, Fig. 4, extends from the pan formed upon the upper portion of the box or chamber 69 and serves to withdraw the water which runs out of the bottles 75 while the spindle-brushes are acting thereon.

Mounted upon the cylinder 61 is a pan or receptacle 85 which forms the support for a series of pipes or manifolds 86, provided with a series of jet tubes 87, one for each bottle in 80 the crate, said tubes being each surmounted by an inverted frusto-conical mouth-piece 88, into which the mouths of the bottles pass when the angle-bars which form the supporting frame for the first crate are lowered. 85 This lowering is effected by the downward movement of the frame 33 and the rods 39, as above set forth, the sustaining springs being sufficiently strong to hold the frame, with the crate and bottles therein, in an elevated 90 position. The downward movement continues until the mouths of the bottles come to rest in the mouth-pieces 88, and any further downward movement will not put a strain upon the bottles, for the reason that 95 they are free to be lifted slightly out of the crate. A drain pipe 89 is provided for the pan-like structure 85.

A pan 90 is mounted upon the bracket 2, said pan being provided with a manifold 91, 100 having a series of jet or spray tubes 92 and mouth-pieces 93, similar to the parts just mentioned. This pan is arranged directly below the frame in which the crate that has just passed from the spindles comes to rest, 105 and the bottles contained in the crate are lowered into contact with the mouth-pieces as the frame 33 and its extended arms are lowered.

In Fig. 7 is shown a slightly modified form 110 of gearing for rotating the spindles. Mounted upon a stub-axle which extends downwardly from the lower portion of the water-box or chamber 94 is a gear 95 and a bevel-pinion 96, the latter meshing with a similar 115 pinion 97 mounted upon a driving shaft 98. Gear 95 meshes with a small gear 99, secured upon the lower end of a shaft 100, said shaft being mounted in a bearing extending from the water-box or chamber and carrying at 120 its upper end a gear 101, which in turn meshes with four gears 102, secured to the lower portions of the spindles 103. The gears 101 will occupy the same position with reference to the spindles and their gears as 125 do the idlers 78, shown in Fig. 4. Any form of gearing may, of course, be employed.

In Fig. 8 the mouth-piece 88 is shown in detail. As will be noted upon reference to said figure, it is provided with a series of slots 130

or openings 88^a, formed between the upper and lower edges of the frusto-conical portion of said mouth-piece. The parts are so proportioned that when a bottle-mouth is placed thereon the slots 88^a stand beneath the mouth of the bottle, so that the water and air may pass out of the bottle-mouth and through said slots or openings while the water-jet or spray is being forced upwardly into the mouth of the bottle through the tube 87. In practice the device has been found very efficient and solves a difficulty heretofore experienced with many such devices, forming a proper support for the bottle and likewise a free exit for the air and water which are forced out of the bottle by the incoming jet or spray.

In Fig. 9 a modification of the mouth-piece is shown. The main body portion 88^b is provided with a central orifice 88^c through which the water is forced, and a series of holes 88^d are drilled through the casting at the lower portion of the mouth-piece proper, so that when a bottle-neck comes to rest upon the mouth-piece, vents or passages are formed through which the air and water may escape from the bottle.

Having thus described my invention, what I claim is:

30 1. In an apparatus for washing bottles, the combination of a base; a series of spindle-brushes mounted thereon; a frame movable toward and from said spindles; means for clamping the bottles in a crate carried by the frame; and fluid-pressure mechanisms for actuating the clamping means and for moving the frame.

2. In an apparatus for washing bottles, the combination of a base; a series of spindle-brushes mounted thereon; a frame movable toward and from said spindles; means for clamping the bottles in a crate carried by the frame; means for raising and lowering the frame; and mechanism, under the control 45 of the operator, for first throwing the clamping means into operation and then bringing the means for raising and lowering the frame, into operation.

3. In an apparatus for washing bottles, the combination of a base; a series of spindle-brushes mounted thereon; a frame movable toward and from said spindles; a plate for clamping the bottles carried by the frame; fluid-pressure mechanism for operating said plate; fluid-pressure mechanism for raising and lowering the frame; and a valve, under the control of the operator, for admitting fluid under pressure to said fluid-pressure mechanisms.

60 4. In an apparatus for washing bottles, the combination of a base; a series of spindle-brushes mounted thereon; a frame movable toward and from said spindles; a plate for clamping the bottles within a crate carried by the frame; means for normally holding

said plate in an elevated position; fluid-pressure mechanism for depressing said plate; and fluid-pressure mechanism for raising and lowering the frame toward and from the spindles.

70 5. In an apparatus for washing bottles, the combination of a base; a series of spindle-brushes mounted thereon; a frame movable toward and from said spindles; a series of mouth-pieces carried by the frame; a track 75 yieldingly supported by the frame and adapted to receive a crate with a series of bottles therein; a plate overlying the bottles; means for forcing said plate downwardly, thereby clamping the bottles in place and 80 moving the mouths thereof into contact with the mouth-pieces; and means for raising and lowering the frame, whereby the spindle-brushes will be inserted into and withdrawn from the bottles.

85 6. In an apparatus for washing bottles, the combination of a base; a series of spindle-brushes mounted thereon; a frame movable toward and from said spindles; a series of mouth-pieces mounted upon the frame; a track 90 for supporting a crate with a series of bottles therein; a plate overlying the bottles; means for moving said plate downwardly, thereby causing the bottles to be moved into the mouth-pieces and to be clamped in such 95 position; means for lowering and raising the frame; and a single controlling device for both of said means, said device bringing the plate-moving means into operation prior to the operation of the second means, and maintaining it in such relation until the frame is 100 again elevated.

7. In an apparatus for washing bottles, the combination of a base; a series of spindle-brushes mounted thereon; a frame movable 105 toward and from said spindles; means carried by the frame for supporting a crate carrying a series of bottles; a clamping plate; a cylinder mounted above said plate; a piston-rod extending downwardly from the cylinder 110 and connected to the plate; means for admitting fluid to the upper end of the cylinder; a second cylinder mounted upon a fixed portion of the apparatus; means for admitting fluid to the lower end of said cylinder 115 beneath the piston therein; a piston-rod extending from the cylinder; and connections between said rod and the frame, whereby when fluid is admitted to the cylinder the frame will be drawn downward.

120 8. In an apparatus for washing bottles, the combination of a base; a series of spindles mounted thereon; a frame movable toward and from said spindles; means for normally holding the frame in an elevated position; a second frame mounted above the first frame; connections between said frames to move the same in unison; a plate interposed between said frames and normally overlying the bottles which are supported by a crate mounted 125 130

upon the first frame; a cylinder carried by the upper frame; a piston mounted in the cylinder; a piston-rod extending from the piston downwardly and connected to the 5 plate; a second cylinder carried by a fixed portion of the apparatus; a piston mounted therein; a piston-rod extending downwardly from the piston; connections between said rod and the frames; and a valve for admitting fluid under pressure first to the first-named cylinder and thereafter to the second-named cylinder and releasing the fluid from 10 said cylinders in the reverse order, whereby the bottles will be first clamped in position 15 and maintained in such position throughout the raising and lowering of the frames.

9. In an apparatus for washing bottles, the combination of a base; a series of spindle-brushes mounted thereon; posts or columns 20 extending upwardly from said base; a frame slidably mounted upon said columns; a series of mouth-pieces carried thereby in alignment with the bottles; a track yieldingly supported above said frame and adapted to 25 receive a crate with a series of bottles therein; a second frame also mounted upon said columns, above the first frame; a plate carried by the columns intermediate said frames; springs normally holding said plate 30 in an elevated position; a cylinder mounted upon the upper frame; a piston working in said cylinder; a rod extending from said piston downwardly and connected to the plate; a pair of rods connecting the frames; 35 a second cylinder mounted upon a fixed portion of the apparatus; a piston working therein; a piston-rod extending downwardly from the piston; a pair of counter-weighted levers of the first order; connections between 40 said levers and the last-named piston-rod; connections between the opposite ends of the levers and the rods which connect the frames; and a valve for admitting fluid under 45 pressure to the cylinders, said valve being so arranged that fluid is admitted to the first cylinder in advance of the second cylinder, so that the clamping plate is moved downwardly into contact with the bottles prior to any movement of the frames.

50 10. In an apparatus for washing bottles, the combination of a base; a series of spindles mounted thereon; a frame movable toward and from said spindles; means for raising and lowering the frame; a pipe communicating with the lower ends of the spindles and serving to supply water or other fluid thereto; a valve located in said pipe; and connections between said valve and the means for raising and lowering the frame, whereby as the 55 frame is lowered and the spindles are moved into the bottles the valve will be opened to admit fluid to the spindles and upon a reverse movement the valve will be closed to shut off the supply of fluid.

60 65 11. In an apparatus for washing bottles,

the combination of a base; a hollow box or chamber mounted thereon; a series of rotatable spindles carried by the box, the lower ends of the spindles opening into the same; a pair of columns extending upwardly from 70 said base; a frame slidably mounted upon said columns; means carried by the frame for holding a crate with a series of bottles thereon; a pair of links extending downwardly from the frame; a pair of levers pivotally connected at one end to said links and fulcrumed upon the base; means for actuating said levers to raise and lower the frame; a pipe extending into the hollow box or chamber; a valve controlling the passage 80 of water through said pipe and consequently through the spindles; and connections between said valve and one of the levers for opening and closing the valve, the valve being opened as the spindles enter the bottles 85 and closed just prior to the withdrawal of the bottles from over the spindles.

12. In an apparatus for washing bottles, the combination of a base; a series of spindles mounted thereon; a series of spray tubes located to each side of the spindles; a frame movable toward and from said spindles; means carried by the frame for supporting a 90 crate with a series of bottles therein; a crate-supporting frame located above each of said series of spray-tubes; means for normally holding said frames in an elevated position; and connections between the first frame and second frames for drawing the second frames down into contact with the spray tubes as the 95 first frame nears its limit of downward movement.

13. In an apparatus for washing bottles, the combination of a base; a series of spindles mounted thereon; a series of spray tubes located to each side of said spindles; a frame movable toward and from the spindles; means carried by said frame for holding a crate with a series of bottles therein; a pair of 100 crate-supporting frames located one to each side of the first frame; means for normally holding said frames in an elevated position; and a loose connection between each of said frames and the first-named frame for drawing said frames downwardly into working relation with the spray tubes as the bottles carried by the first-named frame come into working relation with the spindles by the downward movement of said frame.

14. In an apparatus for washing bottles, 120 the combination of a base; a series of spindles mounted thereon; a frame movable toward and from said spindles; means carried by the frame for supporting a crate with a series of bottles therein; a series of spray tubes 125 mounted to each side of the spindles; a pair of crate-supporting frames located respectively above the spray tubes; means for normally holding said frames in an elevated position; arms extending outwardly from the 130

centrally-disposed frame; rods projecting upwardly from said arms and passing loosely through the outermost frames; and collars mounted upon the rods and serving to contact with the frames and to draw the same downwardly after the centrally-disposed frame has moved down to carry the bottles over the spindles.

15. In an apparatus for washing bottles, 10 the combination of a base; a series of spindle-brushes mounted thereon; a frame slidably mounted above said spindle-brushes; means for raising and lowering the frame; a series of spray tubes mounted to one side of the spindle-brushes; a frame located above said spray tubes; means for normally holding the frame in an elevated position; and connections between said first-named frame and the second frame for drawing the second frame downwardly after the bottles supported by the first frame have been brought into working relation with the spindle-brushes.

16. In an apparatus for washing bottles the combination of a base; a series of spindles mounted thereon; a frame located above said spindles; means for raising and lowering said frame to bring the bottles carried by a crate supported by the frame into working relation with the spindles; a series of spray tubes located upon each side of the spindles; a crate-supporting frame mounted above each series of tubes; springs normally holding said last-named frames in an elevated position; rods projecting upwardly from extensions formed upon the centrally-disposed frame, said rods passing through eyes or openings formed upon the spring-sustained frames; and a pair of collars mounted upon each of said rods, the collars being so positioned that when the centrally-disposed frame is elevated the lowermost collars will contact with the spring-sustained frames and bring the various frames into alinement, while the uppermost collars serve to draw 40 the spring-sustained frames downwardly as

the centrally-disposed frame carries the bottles into working relation with the spindles.

17. In an apparatus for washing bottles, the combination of a base; a series of spindles mounted thereon; a crate-supporting frame movable toward and from said spindles; means for actuating said frame; a series of spray tubes mounted upon each side of the spindles; a crate-supporting frame located over each of said series of spray tubes; means for normally elevating the centrally-disposed frame and the frames over the spray tubes for drawing said frames downward as the centrally-disposed frame is lowered and for bringing the three frames into alinement when the centrally-disposed frame is elevated; and means for moving a bottle-supporting crate from one frame to another while the frames are in alinement. 60

18. In an apparatus for washing bottles, the combination of a base; a series of spindle-brushes mounted thereon; a frame movable toward and from said spindles; a series of spray tubes located to each side of the spindles; a crate-supporting frame mounted above each series of spray tubes; springs serving normally to hold said frames in an elevated position; connections between the centrally-disposed frame and the spring-sustained frames for drawing the latter downward as the centrally-disposed frame carries the bottles supported thereby into operative relation with the brushes, and to bring the various frames into alinement when the centrally-disposed frame is brought to its elevated position; and means for advancing the crates from one frame to another. 75

In testimony whereof I have signed my name to this specification in the presence of 85 two subscribing witnesses.
